UNITED STATES PATENT OFFICE.

MYRON D. EDDLEMAN AND CHARLES E. QUINN, OF CHICAGO, ILLINOIS.

MULTIGRAPH ATTACHMENT.

Application filed November 18, 1925. Serial No. 69,878.

This invention relates to new and useful improvements in jogging devices and has for its principal object the provision of a device of this character which can be 5 expeditiously attached to a multigraph machine for the purpose of jogging printed sheets of paper discharged from the multigraph machine.

A further object of the invention is the 10 production of a device of this character which is arranged and adapted to be attached to a multigraph machine to be automatically operated thereby.

A further object of the invention is to 15 provide a device of this character arranged and adapted to be connected to a multigraph machine to be operated thereby as the machine automatically discharges printed sheets of paper.

20 Other object will appear hereinafter.

The invention consists in the combination and arrangement of parts hereinafter described and claimed.

The invention will be best understood by 25 reference to the accompanying drawings showing the preferred form of construction and in which:

Fig. 1 is a side elevational view of a multigraph machine showing the invention associated therewith,

30 Fig. 2 is an elevational view of the discharge end of the multigraph machine showing the invention associated therewith,

Fig. 3 is a top plan view of the invention,

35 Fig. 4 is a fragmentary sectional view of the invention taken substantially on line 4-4 of Fig. 3,

Fig. 5 is a fragmentary sectional view of 40 the invention taken substantially on line 5-5 of Fig. 3,

Fig. 6 is a fragmentary sectional detail 45 view of a connecting element embodied in the invention,

Fig. 7 is a fragmentary sectional detail 50 view taken substantially on line 7-7 of Fig. 1, and

Fig. 8 is a sectional view of a modified 55 form of construction of the connecting element illustrated in Fig. 6.

As will be apparent from the following

description of the invention our novel jogging device can be attached to any conventional multigraph machine such as is illustrated in Fig. 1 and which comprises as 55 a part thereof a frame 10 carrying a rotatable type drum 11, and an automatic paper feeding arm 12 which feeds the papers to the platen roller 13.

To the frame 10 is attached a hinged 60 paper receiving shelf supported in inclined position by supporting arms 10' and having upwardly extending spaced side walls 14 carried by a bottom 15 having elongated transversely extending slots 16 formed 65 therein for the reception and accommodation of upwardly projecting spaced jogging fingers 17 which are adapted to move transversely of the bottom 15 and slots 16. The jogging fingers 17 are operatively mounted 70 on a slide bar 18 which in turn is mounted on spaced parallel extending slide rods 19 which extend transversely of and beneath the bottom 15, said slide bar being held on the slide rods 19 in the desired adjusted position by set screws 20. The slide rods 19, as best illustrated in Fig. 4 are carried for transverse slidable movement by brackets 21 and 22 having spaced aligned holes through 75 which these slide rods are adapted to work, 80 and these brackets 21 and 22 are carried by the bottom 15. A connecting bar 23 is provided to join the slide rods together at corresponding ends and this connecting bar is operatively connected to a link 24 which in 85 turn is pivotally connected to a bell crank 25 supported for pivotal movement by a screw 26 carried by the bracket 22 as best illustrated in Fig. 4. Arm 25* of the bell crank has a threaded end 27 for threaded 90 engagement with a ball and socket connection 28, the ball being indicated at 29 and the socket at 30. The socket part of this connection has a threaded portion 31 which is adapted to receive an angled end 32, of 95 a connecting arm 33 and hold said connecting arm in operative connection with the ball and socket connection by means of a nut 34. This arm 33 is operatively connected to the automatic paper feeding arm 100 12 as at 35, where the arm 12 is connected to an extension 12' operated by a gear 13'

which operates the feeding arm 12, as best illustrated in Fig. 1. The connection at point 35 is accomplished by means of a shoulder screw 36 having reduced portions 37 and 38 and a threaded portion 39 threaded in the extension 12', the reduced portion 37' being adapted to receive the arm 33 whereas the reduced portion 38 being adapted to receive the end portion 38' of the feeding arm, as best illustrated in Fig. 7.

In Fig. 8 we have shown a slightly modified form of construction of the ball and socket joint illustrated in Fig. 6. This construction is substantially the same as that shown in Fig. 6 with the exception that the connecting arm 33 is provided with a threaded end portion 40 having threaded engagement with the socket portion 30 of the ball and socket connection.

In the operation of a multigraph machine, the paper is automatically fed to the type drum by the feeding arm 12 in the usual manner now employed in machines of this type and as the paper is fed to the drum a printed sheet is automatically discharged therefrom and received by the shelf and as this operation continues the sheets rest on the shelf in disarranged pile form with the edges of one sheet overlapping the edges of the one below. It is therefore an object of the invention to retain the sheets in an even and neat pile so that the same can be conveniently removed at the proper time without first manually jogging the paper and this is accomplished by the use of the jogging fingers which move in the slots transversely of the shelf jogging the pile of printed sheets of paper against the side wall toward which they are moved. The movement of these fingers is in unison with and upon each operative stroke of the feeding arm.

In order to jog the paper sheets of various sizes we have mounted the jogging fingers on an adjustable slide bar which can be adjusted in any desired position on the slide rods beneath the bottom of the shelf.

From the foregoing description and with reference to the accompanying drawings it is apparent that we provide a device which is capable of arranging sheets of printed papers in an even and neat pile thus greatly facilitating the removal of the pile of paper from the receiving shelf.

While we have shown and described the preferred form of our invention it is to be understood that various changes and alterations may be carried out during manufacture without departing from the spirit of the invention or the scope of the appended claims.

Having thus set forth our invention, what we claim as new and useful is:

1. A jogging device including a shelf having a vertically extending side wall, jogging

fingers movable toward and away from the side wall, brackets carried by the shelf, supporting members carried by the brackets for reciprocatory movement transversely of the shelf and carrying the jogging fingers for movement therewith, an operating member pivotally carried by one of the brackets, a member providing a connection between one end of the operating member and the supporting members, and operating means having operative connection with the opposite end of the operating member.

2. A jogging device including a shelf having transversely extending slots formed therein, spaced supporting members mounted for reciprocatory movement beneath the shelf transversely thereof, a supporting bar carried by the supporting members for movement therewith, jogging fingers carried at opposite ends of the supporting bar and extending upwardly through the slots, means providing a connection between the opposite corresponding ends of the supporting members, and operating means having operative connection to said means.

3. A jogging device including a shelf, jogging fingers movable transversely of the shelf, supporting members mounted for reciprocatory movement transversely of the shelf, a supporting rod carried by the members and supporting the jogging fingers for movement therewith, a member connecting opposite corresponding ends of the supporting members, means carried by the shelf and supporting the supporting members for reciprocatory movement, an operating member pivotally carried by said supporting means and having an end portion operatively connected to the member, and operating means operatively connected to the opposite end of the operating member.

4. A jogging device including a shelf having a vertically extending side wall and having transversely extending slots formed therein, brackets connected to the shelf, rod members supported by the brackets for reciprocatory movement transversely of the shelf, a supporting bar carried by the rod members for adjustment longitudinally thereof, jogging fingers carried at the opposite ends of the supporting bar and extending upwardly through the slots, a member connecting opposite corresponding ends of the rod members together, a bell crank pivotally carried by one of the brackets, a link member providing a connection between one end of the bell crank and the member, and operating means operatively connected to the opposite end of the bell crank.

5. The combination with a paper feeding arm, a supporting shelf, jogging fingers mounted for movement transversely of the shelf, means movable transversely of the shelf and supporting the jogging fingers for movement therewith of an operative con-

nection between the movable means and the paper feeding arm, said operative connection including a bell crank pivotally associated with the shelf, a connection between one end of the bell crank and the movable means, a connecting arm having an end portion operatively connected to the feeding

arm, and a universal joint connection between the opposite end of the bell crank and the opposite end to the connecting arm. ¹⁰
In testimony whereof we affix our signatures.
